Assistant Examiner — Christine Tucci

(57) **CLAIM**

The ornamental design for a shoe as shown and described.

DESCRIPTION

FIG. 1 is a top perspective view of a shoe showing my new design;

FIG. 2 is a bottom perspective view thereof;

FIG. 3 is a left view thereof;

FIG. 4 is a right view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is an enlarged view of a portion labeled as "9" on FIG. 1; and,

FIG. 10 is an enlarged view of a portion labeled as "10" on FIG. 2.

The long dash-short dash broken lines depict the cut lines of the enlarged partial views and form no part of the claim.

1 Claim, 10 Drawing Sheets(56)
